KARL ENGEL, OF ARLINGTON, MASSACHUSETTS, ASSIGNEE TO UNITED SHOE MACHINERY COMPANY, OF PATERSON, NEW JERSEY, A CORPORATION OF NEW JERSEY.

BOOT AND SHOE.

1,149,189.

Specification of Letters Patent. Patented Aug. 10, 1915.

Original application filed March 24, 1910, Serial No. 551,292. Divided and this application filed November 3, 1914. Serial No. 870,141.

To all whom it may concern:

Be it known that I, KARL ENGEL, a citizen of the United States, residing at Arlington, in the county of Middlesex and State of Massachusetts, have invented certain Improvements in the Manufacture of Boots and Shoes, of which the following description, in connection with the accompanying drawings, is a specification, like reference 5 characters on the drawings indicating like parts in the several figures.

This invention relates to the manufacture of boots and shoes and is illustrated in connection with that type known as "stitch-downs".

In my co-pending application Serial No. 551,292 of which the present application is a division there is shown and described a counter the lower margin of which in the 20 finished shoe is turned outwardly, said counter being comparatively thin along the line of turn and comparatively thick on each side of said turn one purpose of such a counter being to permit the use of thin lifts 25 in place of the thick lifts which would otherwise be required if the lower outturned margin of the counter were skived as was previously customary. When, however, a back stay is provided in a shoe having a thick 30 lower margin such as this one an undesirable thickness of material results in the edge of the shoe where the outturned end of the back stay overlaps the outturned margin of the upper.

The general object of the present invention is to make the projecting edge of the heel portion of the shoe at the point where the back stay extends over it of substantially uniform thickness with the rest of the 40 edge at that portion. To this end a groove or depression is made in that portion of the margin of the counter which in the finished shoe lies beneath the outturned end of the back stay so that in the finished shoe the 45 upper surface of the outturned end of the back stay may be substantially flush with the upper surface of the outturned margin of the upper.

Referring now to the accompanying drawing, Figure 1 is a perspective of a counter of approved form; Fig. 2 is a cross section of the same on the line 2--2; Fig. 3 is a perspective of a shoe embodying a counter of the form shown in Fig. 1.

In Fig. 1 there is shown a counter of ordinary outline but differing from ordinary counters in having its lower edge 1 of a thickness equal approximately to that of its center or unskived portion 3, the upper curved portion being skived as usual as indicated at 4. In order that space may be provided for the outturned lower portion of the back stay the counter is formed with a depression 5; and for a reason presently to be set forth the edge 1 of the counter is tapered at each end as indicated at 6. Besides the features noted above there is formed in the counter a groove 7 extending from end to end along the lower margin, said groove being deeper at its central portions and becoming gradually shallower toward either end so that the portions indicated at 8 are of approximately the same thickness as the thicker portions of the edge 1.

For convenience the face of the counter which is exposed in Fig. 1 will be termed the inner face since that is a proper designation with reference to its relative position in the assembled shoe. It will be observed then, that the lower edge is of a thickness approximately equal to that of the central portion, that the outline of said central portion corresponds to the outline of the counter, and that the face of the lower edge forms substantially a right angle with the inner face of the counter and may therefore be termed a square edge to distinguish it from the beveled edge 4. It should be noted also that the groove 7 and the depression 5 may be said to represent areas of comparative flexibility.

In Fig. 3 there is shown a shoe made in accordance with the present invention, and for convenience a spring heel shoe has been chosen for illustration. The outturned portion of the upper is shown at 18, the thick edge of the counter at 1, the comparatively thin lift at 9, the inner sole at 10, and the outer sole at 11. Had an ordinary counter been used its lower edge (which would have corresponded to the edge 1) would have been very thin so that to produce a spring heel shoe a thick lift would have been required to fill the space occupied in the illustrated shoe by the thick edge 1 of the counter and the thin lift 9. These thick lifts as well as the counters must be cut from the more valuable portions of the hide while the

thinner lifts may be cut from the less valuable portions. The construction described above, therefore, does away with the necessity for thick, expensive lifts and permits 5 the utilization of a certain portion of the died-out counter which was formerly skived off and discarded.

In the manufacture of shoes of this type the parts of the upper are assembled and the 10 heel molded into shape by a machine comprising a flat yoke which contacts with the upper along the line 12 of the turn and a wiping member which turns the upper outwardly over said yoke and exerts a compressing action on the outturned portion. In this operation the outturned end of the back stay 13 is forced against that portion of counter opposite to the depression 5 so that the outturned margin of said counter 15 together with the outturned margin of the upper at this point is distorted as shown to make room for the back stay and thereby bring the upper surface of the outturned end of the back stay into the plane of the 20 corresponding surface of the upper at either side of it. The result of the depression of this portion of the back stay is thus to render the edge of the lower part of the shoe 25 about the heel portion of substantially uniform thickness.

In order to make a smooth joint between

the ends of the counter and the end of the inner sole the end of the inner sole is beveled as shown and the beveled end 6 of the counter is caused to extend into the V-shaped 35 opening between the upper and the beveled end of the short inner sole.

Having thus described the invention what I claim and desire to secure by Letters Patent is:

1. In a stitch down shoe comprising an upper having an outturned margin and a back stay attached to said upper and similarly outturned, a counter having an outturned portion provided with a depression 45 to provide space for the outturned portion of said stay.

2. In a stitch down shoe having a back stay provided with an outturned end attached to the upper thereof, a counter also 50 attached to said upper and having an outturned portion, said outturned portion of said counter being distorted to provide space for the outturned end of said back stay.

In testimony whereof I have signed my name to this specification in the presence of two subscribing witnesses.

KARL ENGEL.
